UNITED STATES PATENT OFFICE.

GEORGE A. EDE, OF COBDEN, ILLINOIS.

STAPLING-MACHINE.

SPECIFICATION forming part of Letters Patent No. 761,365, dated May 31, 1904.

Application filed March 27, 1903. Serial No. 149,789. (No model.)

To all whom it may concern:

Be it known that I, GEORGE A. EDE, a citizen of the United States, residing in Cobden, in the county of Union and State of Illinois, have invented certain new and useful Improvements in Stapling-Machines, of which the following is a full, clear, and exact description, reference being had to the accompanying drawings, forming part of this specification.

10 My invention relates to certain improvements in that class of machines used in forming and driving staples into veneer boxes or baskets or like articles; and the invention consists in features of novelty hereinafter fully described, and pointed out in the claims.

Figure I is a front elevation of the machine with the face-plate of the staple forming and driving bar housing removed. Fig. II is a longitudinal section of the machine, taken on line II II, Fig. I. Fig. III is a transverse section taken on line III III, Fig. II. Fig. IV is a vertical section taken on line IV IV, Fig. II, the clutch-retaining yoke being shown in elevation. Fig. V is an enlarged vertical section taken on line V V, Fig. IV. Fig. VI is an enlarged horizontal section taken on line VI VI, Fig. IV. Fig. VII is a perspective view of the clutch-receiving finger carried by the retaining-yoke. Fig. VIII is a face view of the 25 staple forming and driving bars, illustrated in the position assumed just previous to driving the staple. Fig. IX is a similar view to Fig. VIII, showing the staple forming and driving bars in the position assumed when the staple has been driven. Fig. X is a section taken through the staple-forming members in the position assumed previous to the act of driving the staple after it has been formed. Fig. XI is a section of the parts shown in Fig. X in 30 the position assumed after the staple has been formed and the reciprocating forming-finger has been retracted previous to the driving of the staple. Fig. XII is a vertical section taken on line XII XII, Fig. XI. Fig. XIII is a vertical section of the upper portion of the die-box. Fig. XIV is a section of two layers of material with a staple formed upon my machine illustrated as driven therethrough. Fig.

XV is a view of the under side of the layers of material shown in Fig. XIV. Fig. XVI is a cross-section on the line XVI XVI, Fig. II.

1 designates the post of my machine, which is surmounted by a table 2.

3 is a frame-upright surmounting the rear end of the table 2 and supporting a hollow forwardly-projecting frame-arm 6.

7 is a housing bearing a face-plate 8 and secured to the forward projecting frame-arm 6 by a neck 9, fitted into said arm.

10 is a bushing seated in the rear end of the frame-arm 6.

11 designates a longitudinal drive-shaft extending through the frame-arm 6 and journaled in the housing-neck 9 and bushing 10.

12 designates a die-box set in the forward end of the table 2 beneath the housing 7. In the box 12 is a vertically-reciprocating die 13, provided with an arm 14 and normally held depressed by a spring 15. (See Fig. II.) The die 13 is operated by mechanism hereinafter described. The die-box 12 is mounted in the table 2 for vertical adjustment therein by an adjustment-screw 12^a, that bears against an arm 12^b, carried by the box. Through the medium of the adjustment-screw the box is raised or lowered and I thereby vary the elevation of the box for the purpose to be hereinafter mentioned. At the lower end of the housing 7 is a guide 16 through which the staple-wire is delivered to the forming and driving mechanism, as will hereinafter appear.

17 is a bracket extending laterally from the lower end of the housing 7, and in which is journaled a shaft 18, that carries a feed-wheel 19. The staple-wire passes between this feed-wheel and a roller 20 beneath it from a guide 21, as illustrated in Fig. I. The shaft 18 extends rearwardly from the bracket 17 and bears at its rear end a ratchet-wheel 22. The ratchet-wheel 22 receives the engagement of a spring-pressed pawl 23, carried by a slotted reciprocating bar 24, that is driven by an eccentric 25, mounted on the drive-shaft 11.

26 designates a cam fixed to the drive-shaft 11 above the vertical opening in the frame-upright 3. The groove in this cam receives the

fork 27 of a lever 28, vibratory supported by a rock - shaft 29, journaled in the wall of the frame-upright 3.

30 is a reciprocating bar pivoted to the lower 5 end of the lever 28 and extending forwardly through an aperture 5 in the frame-upright 3 and leading to the housing 7.

31 is a finger - slide that is detachably connected to the reciprocating bar 30 by a tongue 10 32, projecting from said bar and fitting in a socket in said finger-slide. The slide 31 carries a form-finger 33, which projects forwardly therefrom. The finger-slide 31 is supported by a bracket - guide 34, depending from the 15 housing 7. This slide is detachably connected to the bar 30, by which it is carried, for the purpose of permitting its ready disconnection therefrom and removal for repair or introduction of a new slide to take its place when 20 it becomes worn in the service, to be herein-after referred to. The finger 33 of the slide 31 is adapted to be projected forwardly beneath a vertical box-bracket 34 at the lower end of the housing 7.

25 35 designates a wrist-pin carried by the drive-shaft 11 for rotation within the housing 7.

36 is a driver-bar situated in the housing 7 and provided with a crescent-shaped cam-slot 37, in which the wrist-pin 35 operates. The 30 driver-bar carries a plunger-finger 38.

39 is a forming-bar that is provided with an S-shaped cam-slot 40, which receives the wrist-pin 35 and in part registers with the cam-slot 37 in the driver-bar. The forming-bar 39 has 35 a pair of forming-fingers 41, which straddle the plunger-finger 38 and the inner facing sides of which contain at their lower ends grooves 42. (See Figs. IX, XI, and XII.)

In the practical operation of forming and 40 driving the staples the described mechanism is actuated through the medium of the drive-shaft 11. On the rotation of said shaft the staple-wire A (see Figs. I, VIII, and X) is fed through the guide 16 by the actuation of the 45 feed-wheel 19, which is operated by the eccentric and ratchet mechanism connecting it to the shaft. The staple-wire is thereby fed horizontally across the space 34 beneath the housing 7. At the same time that the staple-wire 50 is fed forwardly through the guide the form-finger 33 is projected into a position beneath the space 34 by the reciprocation of the bar 30, actuated by the lever 28, having engagement with the shaft-carried cam 26. Rotation 55 of the drive-shaft causes the wrist-pin 35 to be carried upwardly and then downwardly in the cam-slots of the forming and driver bars 36 and 39. As said wrist-pin begins to move downwardly in its travel it 60 first acts upon the cam-face at the bottom of the S-shaped slot 40 of the forming-bar and forces said bar downwardly without moving the driver-bar. The forming-fingers 41 are thereby carried to the wire projecting across

the space 34, and the finger near the inner end 65 of the guide 16 severs said wire, so that a short section from which the staple is to be formed will lie across the form-finger 33 beneath the space 34. The forming-fingers 41 continue their downward movement and bend the ends 70 of the section of staple-wire downwardly over the form-finger, thereby producing the staple, the legs of which seat in the longitudinal grooves 42 in said fingers, as seen in Figs. XI and XII. The wrist-pin 35 next begins to act 75 on the cam-face at the lower side of the crescent-shaped cam-slot 37 in the driver-bar in the position seen in Fig. VIII, and as the wrist-pin moves upwardly against said face the driver-bar is carried downwardly to convey the plunger-finger 38 to the staple situated between the forming-fingers 41. During the initial period of travel of the driver-bar the form-finger 33 recedes from its projected position by the reciprocation of the bar 30. 80 Then on the continued downward movement of the plunger-finger 38 the staple is moved downwardly between the forming-fingers until it reaches the material B, (seen in Fig. XI,) 85 into which it is driven. As the staple is 90 driven through the material its legs strike the die 13, and their points are bent on contacting with the die and forced into clenched contact with the material, as seen in Figs. XIV and XV.

By making the die-box 12 vertically adjustable I am enabled to position the die 13 at any desired distance from the forming and driving fingers of the machine, and thereby provide for the driving of staples of varying 100 lengths without danger of their being bent or buckled in forcing them through the box or basket that receives them. Moreover, the thickness of boxes or baskets vary, and it is necessary to provide the requisite space in 105 which all degrees of thickness may be used, which I do by the adjustable mounting of the die-box.

43 designates a treadle pivoted at 44 to the post 1 of the machine, and through which the 110 driving mechanism of the drive-shaft 11 is controlled. To the rear arm 45 of the treadle is pivoted a connecting-rod 46, that leads upwardly to a clutch-retaining yoke 47, which is normally held in a lowered position by a 115 spring 48. (See Fig. II.) The yoke is slidably fitted to a stud 4, projecting from the frame-upright 3, and it contains a slot 49, that receives the drive-shaft 11, with respect to which the yoke is capable of vertical movement. For the purpose of preventing the yoke from riding on the drive-shaft to occasion wear of the parts a boss 50, which moves in a groove 6^a in the rear face of the frame-arm 6 and when at rest at the bottom of said groove supports the retaining-yoke off of the drive-shaft 11. (See Figs. IV and V.)

51 is a stop-block attached to the retaining-

yoke 47 and provided with an inclined face 52, as shown in Fig. VII.

53 is a hardened plate secured to the retaining-yoke alongside of the drive-shaft 11.

54 is a loose pulley mounted on the outer end of the drive-shaft 11, and 55 represents dogs carried by said pulley.

56 is a clutch keyed to the drive-shaft 11 between the retainer 47 and the loose pulley 54. In this clutch is a bolt 57, that is provided with a projecting arm 58 and is backed by an expansion-spring 59. When the machine is at rest, the loose pulley 54 is rotated freely on the drive-shaft, while the clutch 56

is held from rotation by the arm of the bolt 57 engaging behind the stop-block 51 against the inclined face 52. When the machine is put into operation by depressing the treadle 43, the retaining-yoke 47 is moved upwardly

and the stop-block carried away from the bolt-arm 58, thereby permitting the spring 59 to project the bolt 57 toward the loose pulley 54. One of the dogs 55 then engages said bolt and causes rotation of the clutch, and

consequently of the drive-shaft to actuate the staple forming and driving mechanism of the machine. When it is desired to stop the operation of the machine, pressure upon the treadle is relieved, and the spring 48 carries

the retaining-yoke 47 downwardly, with the result that the bolt-arm 58 passes into a position back of the stop 51 and effects stoppage of the clutch and drive-shaft until the retaining-yoke is again elevated.

35 For the purpose of preventing sudden jar and wrenching of the mechanism of the machine in stopping the drive-shaft and its clutch I provide a cushion-pin 60, located in a barrel 61, carried by the retaining-yoke 47 (see

40 Figs. IV, V, and VI) and backed by a spring 62. This cushion-pin receives the clutch-bolt arm 58 when it passes back of the stop 51 into the position seen most clearly in Fig. VI. To prevent recoil of the clutch 56 on striking

45 the cushion-pin 60, I provide a spring-pressed stop-pin 63, set into the clutch and projecting from its inner face toward the retaining-yoke 47. This recoil-pin passes across the hardened stop-plate 53 when the clutch is brought

50 to rest and projects into a recess in the retaining-yoke, as seen in Fig. VI, where it acts to stop retrograde rotation of the clutch when the bolt-arm 58 has struck against the cushion-pin 60 in its stoppage.

55 Each time that the staple forming and driving mechanism of the machine is operated to produce a staple and present it to the die 13 said die is carried vertically toward the approaching forming and driving fingers 38 and 41 by mechanism that will now be described.

64 designates a rotatable shaft extending longitudinally of the machine and having its rear end supported in a swinging journal-box pivotally mounted in a bracket-arm 65. The

rear end of the shaft 64 bears a crank 66, that 65 is connected by a pitman 67 to a crank 68, carried by the drive-shaft 11, through the medium of which the rotatable shaft 64 is driven. Fixed to the forward end of the shaft 64, which passes through and has vertical play in a slot 70 in a web depending from the table 2, is a crank 69, that has bearing in the die-box 12 and bears a pin 70, adapted to engage the arm 14 of the reciprocating die 13 in each rotation of the shaft 64. During the rotation of the main 75 drive-shaft 11 reciprocation is constantly imparted to the pitman 67, and the crank 66 is rotated to impart like movement to the shaft 64 and crank 69. Whenever the die-box 12 is shifted vertically, it will be seen that the 80 forward end of the shaft 64 may rise or fall therewith by moving in the slot in the web depending from the table, this rise-and-fall motion being permitted in consequence of the swinging mounting of the gear end of the shaft 85 64 in the bracket 65. As the staple forming and driving fingers move downwardly toward the die 13 in each operation, the shaft 64, by its connection with the drive-shaft, is rotated, and the die is reciprocated by the crank-pin 90 70 striking the arm of the die. The fingers and die are therefore carried toward each other, and pressure against the staple is exerted both from above and below to quickly and efficiently clamp the staple when driven 95 through the thicknesses of material it secures. The spring 15 returns said die to lowered position after each upward movement thereof.

I claim as my invention—

1. In a stapling-machine, the combination 100 of a drive-bar provided with a crescent-shaped cam-slot, a plunger-finger carried by said bar, a forming-bar provided with an S-shaped cam-slot adjacent to said drive-bar and reciprocating relatively thereto, and a crank-shaft carrying a wrist-pin which registers with said crescent-shaped and S-shaped cam-slots and imparts reciprocating movement to said drive-bar and forming-bar.

2. In a stapling-machine, the combination 110 of a drive-bar provided with a crescent-shaped cam-slot, a plunger-finger carried by said bar, a forming-bar provided with an S-shaped cam-slot adjacent to said drive-bar and reciprocating relatively thereto, a pair of forming-fingers carried by the forming-bar and straddling said plunger-finger, and a crank-shaft carrying a wrist-pin which registers with said crescent-shaped and S-shaped cam-slots and imparts reciprocating movement to said drive-bar and forming-bar.

3. In a stapling-machine, the combination 125 of a drive-bar provided with a crescent-shaped cam-slot, a plunger-finger carried by said bar, a forming-bar provided with an S-shaped cam-slot adjacent to said drive-bar and reciprocating relatively thereto, a crank-shaft carrying a wrist-pin which registers with said

crescent-shaped and S-shaped cam-slots, a reciprocating die, and means for reciprocating said die toward said forming and driving bars, substantially as set forth.

5 4. In a stapling-machine, the combination of staple forming and driving bars, a form-finger bar, a tongue carried by said bar, a slide provided with a socket to receive said tongue to detachably connect said slide to said

bar, and a form-finger carried by said slide, substantially as set forth.

In testimony whereof I have hereunto set my hand this 7th day of March, 1903.

GEORGE A. EDE.

In presence of—

JOHN McCAFFREY,
R. L. RICH.
